UNITED STATES PATENT OFFICE.

MARTIN J. CARNEY; OF TOLEDO, OHIO, ASSIGNOR OF ONE-HALF TO JOHN M. WHEELER, OF SAME PLACE.

TELEPHONE CENTRAL-OFFICE SWITCH.

SPECIFICATION forming part of Letters Patent No. 258,886, dated June 6, 1882.

Application filed October 14, 1881. (No model.)

To all whom it may concern:

Be it known that I, MARTIN J. CARNEY, a citizen of the United States, residing at Toledo, in the county of Lucas and State of Ohio, have invented certain new and useful Improvements in Telephone Central-Office Switches; and I do hereby declare the following to be a full, clear, and exact description of the invention, such as will enable others skilled in the art to which it appertains to make and use the same.

The general object of my invention is to facilitate the work of connecting and disconnecting subscribers' lines at the central-office switch, and to make it possible to do the necessary work with a less number of operators and with less noise and confusion than has hitherto been the case.

My invention relates more particularly to that class of switch-boards known as "sectional boards," in which the subscribers' lines between which communication is most frequently desired are assigned and connected to one of the sections of the switch, and the work of receiving and sending calls and making connections between the subscribers of that section is done entirely upon that section of the board, while if the subscriber of one section makes known to the operator of his section that he desires communication with the subscriber of some other section additional local signals and connections between the two sections are brought into play, and the two subscribers are placed in communication by suitable manipulation of both sections of the switch by the two operators assigned to those sections.

The special object of my invention is to provide a simple and effective means, and one capable of being put into a small compass, whereby the operator at any section of the switch may place any subscriber of that section in communication with the subscriber of any other section without the assistance of other operators or attendants, at the same time allowing the operations of connecting and disconnecting subscribers of the first-named section to be performed in the ordinary way.

My invention consists in certain special combinations of supplemental line strips or plates and supplemental instrument and line connecting strips, which are stated in the claims,

and which will be more readily understood from the accompanying description and drawings.

My invention also consists in a certain novel construction of a switch-plug adapted for use upon plug switch-boards.

In the accompanying drawings, Figure 1 is a diagram or plan illustrating the circuits and connections upon a telephone switch-board of sections, three of the lines only being shown as connected, for the sake of clearness. Fig. 2 shows a modification and illustrates an arrangement of the various portions of a board having a larger number of subscribers' lines connected thereto. Fig. 3 shows a longitudinal and an enlarged transverse section of an improved switch-plug, and an enlarged detail vertical section of the lower portion thereof.

Referring to Fig. 1, A, B, and C represent the three sections of the board, to each of which is connected a set of lines between which communication is frequently desired. The annunciators for the lines proper of each section are located at their sections within view of the operator having charge of the section, and the calls from the subscribers of that section are received only by him.

The operation of connecting the wires of any one section and of signaling to subscribers upon those lines is performed in the ordinary way. Should an order be received from any subscriber for connection with a subscriber whose calls are received at any other section, the latter is called by the operator of the first subscriber, and the lines are connected at the section of the board to which the wire of the subscriber giving the order is connected. The special arrangement of circuits by which this is accomplished, and the special apparatus employed for the purpose of giving compactness to the switch and of putting all the wires of even a very large switch within the control of the operator of each section, will be now described.

Three main or principal line-strips of a plug switch-board are represented by the letter *a* in section A, by *b* in section B, and by *c* in section C. Each of these line-strips is connected to one of the lines of the section to which it belongs, and from each line strip the

5 circuit is to earth through an annunciator of any desired kind, located at the section of board to which the line is immediately connected, and plates *d*, joined by plug-connections, as indicated, with a plate connected to earth.

Included in the circuits of the various line-strips and the ground-plate are supplemental line plates or strips located in the other sections of the apparatus. The supplemental line-strips through which the line circuits for section A pass are shown in section B at the supplemental section A *b*, and in section C at A *c*. Similarly the supplemental boards or sections 10 in sections A and C, through which the lines of section B pass, are indicated at B *a* and B *c*, respectively, and those in A and B, for the lines of C, by C *a* and C *b*, respectively. Taking, for instance, the left hand line, or line 1, of section 15 A, its circuit is as follows: Entering its line-strip *a*, the circuit is through a plug and terminal plate, *f*, to a supplemental line strip or plate, *g*, in B section of the board, through a terminal plug and switch-plate, *h*, to a supplemental line-strip, *l*, in section C of the board, through a terminal plate and plug, as shown, for said plate; thence in reverse order through a plate, *i*, and a plug and plate, *k*, in section C, and similar plates and plugs in section B, 20 to an annunciator, D, a plate, *d*, in section A, and to a plug and plate connected to earth. In a similar manner line 1 in section B is connected through a correspondingly-numbered supplemental line-strip, *m*, of section A, a supplemental line-strip, *l*, in supplemental section 25 B *c* of section C of the board, and in reverse order through the plates *i* *k* of sections C and A, and to ground at section B, first passing through an annunciator. By tracing the connection from C it will be observed that line 1 of 30 that section is also connected to ground through corresponding supplemental line-strips in C *b* and C *a*, and in reverse order through their corresponding plates and plugs, *i* *k*. Similarly 35 all the other lines in each section are taken to earth through correspondingly-numbered supplemental plates in all the other sections and through the proper plates *i* *k* of those sections in reverse order.

40 E and F represent principal line-connecting strips in each section of the apparatus, said strips being adapted to connect any two of the line-strips *a* *a* or *b* *b* by the insertion of connecting-plugs in the well-known manner, or 45 to be connected to any line-strip separately.

45 E' and F' represent supplemental connecting-strips joined to the principal line-connecting strips in each section, and adapted to be connected with any one of the supplemental line-strips *g*, *l*, and *m* in the various sections.

50 K K represent instrument strips or plates, one for the principal board of each section, to which are joined telephone communicating and signaling apparatus of any desired kind, 55 consisting of a receiving-telephone, T, battery-transmitter M, and magneto-generator N for

sending signaling-currents, the latter being provided with a normally-closed shunting-key, P, which may be constructed in any suitable manner, so as when depressed to break the short circuit around the generator, thus causing its currents to be sent to line.

55 Supplemental instrument-strips R, connected with the main instrument-strips K, extend over the vertical series of plates *i* in the supplemental portions of the various sections, and may be connected with any one of the plates *i* by the insertion of a plug, which, in the proper operation of the switch, should be the plug connecting plates *i* and *k*, so that in the act of 60 connecting the signaling apparatus of any section to a supplemental line-plate and to the line belonging to some other section the drop-annunciator of the latter section and the plate through which that line may be connected with its main or principal instrument-strip, as well as the plate *i* of intermediate supplemental boards, will be disconnected. By this means the annunciator of that section is not affected, and, moreover, it is impossible for the operators at the main or principal section and at the intermediate sections to create confusion by attempting to signal at the same time that a signal is being sent from the supplemental instrument-strip of some other section.

65 By the above construction the operator of each section can, through the supplemental instrument-strip R, send a call to the line proper of any other section, since, as has been described, the line-circuit for every wire of every other section passes to earth through a supplemental plate and plug, *i* *k*, in all others. He can also connect any wire upon his main or principal board with the wire of any other section of the board through either of the supplemental line-connecting strips E' F', the latter being common to the supplemental line-strips of the section, and the supplemental line-strips themselves representing and being connected with the line-wires of all other sections. Moreover, this portion of the apparatus can be put in small compass, as the instrument and line-connecting strips are continuous strips, and are common to all the plates *i*, and the supplemental line-strips of any one section, while the plates *i* and the supplemental line-strips can be made of very small dimensions, the length necessary for the latter being only that which will be sufficient to accommodate the maximum number of supplemental line-connecting strips required. Under ordinary circumstances the number of the latter would be but few.

70 The operation of the apparatus is as follows: If a call be received from a subscriber of line 1, section A, the annunciator of that line would indicate the fact to the operator of that section, the path of the current to the annunciator being, as before described, through supplemental line-strips in sections B and C, and in reverse order through corresponding plates, *i* *k*. The operator would thereupon connect the

- telephone apparatus M T with that line by removing the plug from ground connection plate *d* and inserting it in instrument-strip K, thus connecting the latter to plate *d* and to the line 5 through the supplemental line-strips of the other sections. If the call be for a subscriber in the same section, that subscriber would be called by connecting the plate *d* of that line to the instrument-strip K, and the signal would 10 be given in the ordinary way by the magnetomachine, the short circuit of the latter being broken by the push-button P to cause its currents to flow to line. Should that line be already in use at the supplemental board of 15 some other section, that fact would be made known to the operator by the absence of noise caused by the currents from the machine in his receiver T, this being due to the severing of the line-circuit in some other board at the point 20 *i k* or at the terminal plate *h*, in the manner to be presently described. The signal having been given, the lines would be connected in the ordinary way by the insertion of plugs in one of the line-connecting strips E F. In performing 25 this operation the plug connecting the two line-strips with the terminal plates *f* should be withdrawn, so as to break the connection of the lines to the supplemental line strips and connection-plates *i* of other sections, thus making 30 it impossible for the operators of other sections to signal to the lines while connected. The operation of connecting a line of section A to a line of section B would be as follows: The call having been received in the ordinary 35 way, the operator at A would proceed to connect his instrument-strip with the desired line of section B by making plug-connection between his supplemental instrument-strip R and the plate *i*, through which the circuit of the line 40 desired passes. Let it be supposed that line 1 of section B is the line with which communication is desired, and that the plug connecting plates *i k* of that line upon supplemental board B *a* has been withdrawn and inserted in strip R, so as to connect the latter with the plate *i*. The circuit from the signaling apparatus of A would then be through instrument-strip K of section A, supplemental strip R, plate *i* of line 1 in supplemental section B *a*, plates *k i* of line 45 1, supplemental section B *c*, terminal plate *h* and supplemental line-strip *l* in that section, terminal plate *h* and supplemental line-strip *m*, line 1 of supplemental section B *a*, thence directly to principal line-strip *b*, line 1 of section B, through its terminal connecting-plate, and to subscriber's line 1 of section B. 55 At the same time, by the removal of the plug connecting plates *i k* in section B *a*, the connection of the line with its annunciator and plate *d* under instrument-strip K in main section B would have been broken, so that the act of signaling from section A to the line would not give a false signal upon the annunciator of section B, and the operator of section B would also be prevented from signaling the line at the same time through K and *d* of section B; annunciator, and plates *k i* of supplemental section B *a*, &c. Line 1, section B, having been called, the two lines would be connected by withdrawing the terminal plug connecting plate *m*, line 1, section B *a*, with its terminal plate *h*, and inserting it in one of the supplemental line-strips E F', the terminal connecting-plug at *f* of principal line-strip *a*, line 1, section A, having been also withdrawn 70 and inserted in the corresponding line-connecting strip, E or F. The removal of the plug at *h* would secure the two connected lines from interruption from other sections of the apparatus by breaking the connection of supplemental line-strip *m* with strip *l*, plates *i k*, and instrument-strip R of supplemental section B *c*, and with plates *i k*, section B *a*, and the plate *d* for instrument-strip K of main section B. In a similar manner the removal of the plug at *f*, 80 line 1, section A, would prevent interruption by an attempt to signal to that line from supplemental sections A *b* and A *c* of sections B and C, as can readily be seen by following the circuits. The want of continuity in the two line-circuit connections at *f* and *h* would also make known to the operators at B and C that the lines were in use, since in this case on attempting to send the signal no sound would be heard in the receiver T. 85
- 90
- 95
- From the above it will readily be seen that when a line is in use, either upon the principal board or upon the supplemental board of any section, interruption from any other section cannot take place. For instance, if line 1, section C, be in use upon the main or principal board, the removal of the plug at *f*, which is done for the purpose of connecting the line-strip to the line-connecting strip will cut off the supplemental boards C *b* and C *a*. If that line be in use at board C *b*, the removal of the plug at *h*, which is used for connecting the supplemental line-strip to the supplemental line-connecting strip, will cut off the supplemental board C *a* and the signaling and communicating apparatus at C. In the same way it would be impossible for operator at section A to signal to line 1 assigned to his board if that line be connected by means of the supplemental line-plate and line-connecting strip 105 upon some other section with a main or principal line of the latter, since the continuity of the circuit from his instrument-strip K and connected plate *d* to line 1 would be broken at one of the points *h* in a supplemental section. 110
- 115
- 120
- I have not here shown any special devices for giving a signal for disconnection to the central office from connected subscribers, since various devices may be used for this purpose—as, for instance, the well-known device of a high-resistance indicator connected in a branch to ground from the line-connecting strip. 125
- If desired, the call-annunciators for the lines might be placed between the line and the switch-board, so that when two lines are connected the annunciators would be between them. In this case, however, the act of sig- 130

naling from the supplemental switch-board of one section to the line proper of another section would operate the annunciator, and thus give rise to confusion.

5 If desirable, the plates *i* may be placed at one side of the strips *R* instead of beneath them, as shown, although for compactness the latter plan is preferable.

In the modified arrangement shown in Fig. 10 five line-strips are shown in each of the three main sections A B C, and the two supplemental boards or sections are ranged side by side instead of vertically one above the other. The latter plan renders it necessary to duplicate 15 the supplemental instrument-strips and the supplemental line-connecting strips. Both supplemental line-connecting strips in each main section are, however, connected with the same principal line-connecting strip, and the two 20 supplemental instrument-strips are also connected to the same principal instrument-strip. The general arrangement and connections are in other respects substantially the same as in Fig. 1.

25 When a switch is divided into a large number of sections it may be necessary to arrange three or more supplemental sections in the same horizontal line, other sections being placed vertically beneath the others to any desired number, to be determined by the circumstances of the case. The various line-connecting and instrument strips in the same vertical line would preferably be made continuous. Other dispositions of the various sections will readily suggest themselves to those skilled in the art. In 35 the practical construction of the switch the supplemental line-strips could be made of very small dimensions, and no difficulty would be found in bringing all the lines of the largest 40 change within the control of each operator for the purpose of signaling to any line and making the desired connection between any two lines, calls being received by each operator only from the lines assigned to his section.

45 It will be readily seen from the foregoing description that it is not even necessary to place the various sections of the apparatus in the same room, and that, if necessary, they may be placed in different rooms, or even in 50 different buildings.

The improved switch-plug shown in Fig. 3 consists of a stem or spindle, 5, reduced in diameter at its middle portion, and having secured at its lower end in any suitable manner 55 two semi-cylindrical springs, 44, which may be either constructed separately and secured by screws to the lower end of the stem, or may be cast in one piece with the enlargement at the lower end of the stem, the reduced portion 60 of the stem being constructed separately and afterward screwed into the enlarged portion. As thus constructed the plug insures good connection between the upper and under plates of the board, since the end of the plug is seated 65 firmly in the socket in the lower plate, while

the springs make firm contact with the edges of the opening in the upper plate.

What I claim as new, and desire to secure by Letters Patent, is—

1. The combination, in each section of a sectional telephone switch-board, of line strips or plates connected to the lines assigned to that section, connecting strips or plates adapted to be connected to said line-strips, a series of supplemental line-strips interposed in the circuit 70 of the lines assigned to and connected with line-strips on another section of the apparatus, and a connecting-strip common to said supplemental strips, and with which any one of said supplemental strips may be connected, said 75 latter connecting-strip being joined to the plate or strip which is adapted to make connection with principal line strips or plates of the first-named section.

2. A sectional telephone switch-board each 85 section of which contains a set of principal line-strips and means for connecting any two line-strips for oral communication, one or more sets of supplemental line-strips, the number of 90 said sets being one less than the whole number of sections, each of said line-strips forming a portion of a loop from a principal line-strip and the ground connection plate of another section, supplemental connecting-strips 95 connected with the principal line-strips of the section, and a supplemental instrument-strip adapted to be connected with the loop at a point between the various supplemental line-strips and the ground connection plate in which 100 said loop terminates.

3. The combination, with the principal line-strips and the ground connection plates of one section of a sectional switch-board, of leading-wires connected to said line-strip and containing corresponding supplemental line-strips in 105 another section, return-wires connected to the ground-plates, connecting-plates and switch-plugs normally interposed in said return-wires, and a supplemental instrument-strip combined 110 with said connecting-plates, the whole arranged in the manner described, so that when any one of said plugs is shifted to the instrument-strip the connection of a return-wire with a normally-connected ground-plate is broken, and connection is at the same time made between 115 the instrument-strip and a principal line-strip of the first-named section.

4. The combination, with the principal line-strip in one section of a sectional switch-board, of a leading-wire passing through supplemental 120 line-strips in the other sections, a return-wire adapted to be connected with a supplemental instrument-strip in each of said sections, switch-plugs normally forming a part of the leading-wire, as described, and supplemental connecting-strips, the whole combined in the manner described, so that said plugs may be removed 125 and used for connecting a supplemental line-connecting strip with a supplemental line-strip, and so that at the same time the continuity of 130

the leading and return wire will be broken and the use of the supplemental instrument-strips in other sections for sending signals be prevented.

5. The combination, in each section of a sectional switch-board, of main or principal line-strips and connecting devices adapted to connect any of the lines assigned to that section, one or more sets of supplemental line-strips, 10 the strips in each set being connected in local circuits or loops leading from the corresponding principal line-strips of another section or sections and terminating in the ground-connecting plates of that section or sections, and 15 connecting-strips joined to the principal connecting devices of the first-named section, and adapted to make connection with the supplemental line-strips in the latter section, all combined in the manner and for the purposes set 20 forth.
6. The combination, in each section of a sectional switch-board, of line-connecting and indicating devices for the lines assigned to that section, signaling and communicating apparatus adapted to be placed in connection with any one of said lines, a series of supplemental 25 plates placed in the circuit of lines assigned to another section of the switch-board, and interposed between the line strips or plates and the 30 ground-plates of that section, an instrument strip or plate common to said series of supplemental plates and connected to the signaling

apparatus of the section in which said plates are located, and switch-connecting plugs forming a portion of and adapted to preserve the 35 continuity of the loops or connections in which the plates are normally connected, or to connect said plates to the instrument-strip, at the same time breaking the normal connection.

7. The combination, with a sectional telephone switch-board apparatus, in which the line-circuits for each section pass to and through supplemental devices in the other sections, of annunciators for each section, placed in circuit between the earth and the supplemental devices of other sections, so that when connection is made with said circuit upon the supplemental portion of other sections for the purpose of signaling to a subscriber's station from such other sections the annunciator at 50 the central office may be cut out and a false signal at the section of board to which the annunciator belongs be prevented.

8. A switch-plug consisting of a stem or spindle having attached to its lower end two 55 semi-cylindrical springs embracing the stem and free at their upper ends, substantially as described.

In testimony whereof I affix my signature in presence of two witnesses.

MARTIN J. CARNEY.
